DISPLAY STAND

Harry Brownstein, Warren, Ohio, assignor of
one-half to Samuel Mark London, Girard,
Ohio

Application May 12, 1937, Serial No. 142,245

3 Claims. (Cl. 211—28)

This invention relates to display stands and more particularly display racks of the type adapted to exhibit large bodies such as bed springs, mattresses or combinations of bed springs and mattresses.

It is the object of the present invention to provide a display stand which is compact, light in weight, and economical to manufacture. An additional feature of the invention is the convenient collapsibility of the stand when not in use, thereby requiring minimum storage space.

The invention further comprehends a display stand which may be adjusted to vary the supporting element thereof so that the assembly is always in a stable condition and is not subject to accidental overturning or tipping.

Another object of the invention is to provide a display stand for springs and mattresses in which the spring is fixedly maintained in place in order not to permit any jarring movements thereof to affect the positioning of the mattress under display.

It is a further object of the invention to provide a display stand for springs and mattresses fitted with a framed receptacle for storing one or more mattresses in rolled-up condition in addition to the one under display in its fully extended position.

Other objects and purposes will appear from a more detailed description of the invention following hereinafter taken in conjunction with the accompanying drawings, wherein:

Figure 1 is a side elevation of a display stand in accordance with my invention showing a spring and mattress in displaying position,

Figure 2 is a front elevation of Figure 1,

Figure 3 is a plan view of the display stand,

Figure 4 is a longitudinal sectional view along line 4—4 of Figure 3,

Figure 5 is a front elevation of a different embodiment of the invention with the lower portion of a spring shown in position thereon,

Figure 6 is a plan view of a display stand of the type shown in Figure 5, and

Figure 7 is a longitudinal sectional view along line 7—7 of Figure 6.

The display stand in accordance with the present invention is designed to support a spring and/or mattress upon the ends thereof and extending in an upwardly direction in order to adequately display these articles. The stand is designed to be moved from place to place as the needs therefor arise, as is the case in furniture stores, and may be collapsed in order to take up

the least amount of room when the same is not in use.

In Figure 1, is shown a horizontal base frame 1 which may be formed from two lateral steel angle-irons 12 and 13 of about 1 inch width and $\frac{1}{8}$ inch thickness, a rear bar 14 and a front portion 2 which preferably has an angular rise for purposes described hereinafter and terminates in a front bar 11. The base frame is supported on a plurality of rollers 7 which are attached to the underside thereof. Although the rollers are rotatably mounted in their bearings, the mountings themselves may be fixed so that they are incapable of rotating upon the frame. Adequate mobility to the structure is imparted by such a design.

An upwardly extending frame 3 having a top bar 4 is pivotally attached to the rear portion of the frame 1 by means of rivets 8, or bolts and nuts, or like devices. This frame 3 may be braced by arms 5 extending between the frame 3 and the frame 1. The point of engagement of each of these arms with frame 1 may be adjustable by providing a plurality of apertures 21 or a continuous slot having depressions therein adapted to fix by means of bolts or pins 22 the positioning of the arms 5 and the consequent inclination of the frame 3. Thereby the supporting portion 3a of the frame 3 against the bodies to be supported such as the spring 10 and the mattress 20 may be varied in order to dispose the center of gravity of the displayed articles within the boundary of the base frame 1 in order to render the unit stable and not subject to accidental tipping.

In the preferred form of construction shown in Figure 3, a bracing arm 16 extends between the lateral arms 12 and 13 of the base frame and a spacing frame composed of lateral arms 18 and an upwardly extending arm 19 is attached thereto. This spacing frame serves to confine the location of the end of the spring to an intermediate portion of the base frame, as shown in Figure 1.

In order to obtain a lightweight construction and one which is more economical to produce, the display stand may be of lesser width than the spring and/or mattress to be displayed. Thus the frame in Figure 3 may have a length of only two feet and a depth slightly greater than two feet. As shown in Figure 3, a support is provided for the end of the mattress which may be a plane wooden board or a telescopic steel shelf 15—15', in order to provide a support of the mattress without drooping at the ends. In the

form of the invention shown in Figures 3 and 4, the board in its collapsed condition fits within the confines of the frame between the bars 12 and 13 and results in a compact unit for storage. In 5 the collapsed condition of the display stand, the upwardly extending frame 3 folds up closely against the frame 1, which is permitted by the gaps occasioned by the bar 16 terminating short of the vertical flanges of the arms 12 and 13.

10 The angular rise 2 of the base frame 1 is shaped therefrom so that it supports flatly the end of the mattress under display in its inclined position. The portion 3a of the frame 3 is shaped similarly so that it may abut closely the portion 2 in the 15 collapsed condition of the display stand.

In the form of the invention illustrated in Figures 5 to 7, a base frame 31 is provided with rollers 7, for a width corresponding to that of the mattress and/or spring to be displayed. A 20 bracing member 39 extends between the end angle-irons 31 in order to brace the structure, and additional bracing means 32 are provided between bars 31 extending at spaced points in parallel to the angle-irons 31 between the bar 39 25 and the front bar 33.

A V-shaped frame formed by angle-irons 35 and 36, mounted upon the rear portion of the angle irons 31, terminates in upper bars 45 and 46, respectively, and are spaced by spacing bars 30 37 near the upper ends thereof. This V-frame is braced by bracing arms 38 extending between arm 46 and bar 33. The horizontally extending arm 46 serves to support the spring and mattress disposed upon the display stand.

35 A channel 42 is mounted at the rear of the base frame 31 adjacent the rear bar 34, and the rear portion of the V-frame is braced by bracing arms 35' extending between the upper arm 45 and the flange 42' on the channel 42. The space 40 between the bracing arms 38 and 35' extending for the width of the display stand provides a convenient storage space for mattresses in rolled-up condition which may be displayed in conjunction with or independently of the mattress in its 45 fully opened position at the front of the display stand.

Expedients for the adjustment and relative inclination of the parts of the display stand illustrated in Figures 5 to 7 may be provided in a 50 manner shown in detail in the embodiment illustrated in Figures 1 to 4.

While I have described my invention as em-

bodied in concrete form and as operating in a specific manner for purposes of illustration, it should be understood that I do not limit my invention thereto, since various modifications will suggest themselves to those skilled in the art 5 without departing from the spirit of my invention, the scope of which is set forth in the annexed claims.

What I claim is:

1. A display rack for supporting a mattress or 10 spring body in upstanding position, comprising a horizontal rectangular metallic frame disposed close to the floor level adapted to support the body at the front portion thereof with a rearward inclination, a second metallic frame pivotally connected to the rear end of said first frame and adapted to extend upwardly therefrom with an adjustable inclination, said second frame embodying a horizontal bar for supporting the body at a portion thereof resulting in a stable mounting thereof, and adjustable means connected to 20 said two metallic frames for varying their relative inclination.

2. A display stand for holding a mattress or 25 spring body in upstanding position, comprising a horizontal rectangular metallic frame of lesser width than said body, an angular rise forming an extension of said frame, a support overlying said extension of sufficient width to carry the end of the body, a metallic frame extending upwardly from the rear end of said base frame having a width corresponding thereto, means for pivotally mounting said last mentioned frame to said base frame, and means for adjusting said frame to assume varying inclinations for supporting the body at a portion thereof.

3. A display stand for holding a spring and mattress body in upstanding position adjacent to each other, comprising a horizontal rectangular metallic base frame adjacent the floor level having an angular rise at the front end thereof adapted to support the end of the mattress body, a spacing bar extending upwardly for a small extent from said base frame to the rear of said rise for spacing the spring from the mattress, 45 and a supporting member pivotally mounted at the rear of said base frame, and means for varying the inclination thereof to vary the point of support of said spring and mattress assembly upon said supporting member.

HARRY BROWNSTEIN.
